HANDLE FOR MOTOR HAND TOOLS

Filed Jan. 29, 1923

2 Sheets-Sheet 2

UNITED STATES PATENT OFFICE.

BLUFORD W. BROCKETT, OF CLEVELAND HEIGHTS, OHIO, ASSIGNOR TO THE VAN DORN ELECTRIC TOOL COMPANY, OF CLEVELAND, OHIO, A CORPORATION OF OHIO.

HANDLE FOR MOTOR HAND TOOLS.

Application filed January 29, 1923. Serial No. 615,559.

To all whom it may concern:

Be it known that I, BLUFORD W. BROCKETT, a citizen of the United States, residing at Cleveland Heights, in the county of Cuyahoga and State of Ohio, have invented certain new and useful Improvements in Handles for Motor Hand Tools, of which the following is a specification.

This invention relates to motor driven hand tools and particularly to drills, reamers, grinders and other similar devices of this type.

In a copending application Serial No. 615,557 filed of even date herewith by the same applicant, for motor hand tools, there is disclosed a device of this character including a casing having a tool operating shaft, a motor in the casing for operating the shaft, and a plurality of connectors arranged in different positions, as on the end and bottom of the casing, and adapted for engagement with a removable pistol grip or a handle having connectors in different positions and all connected to a supply cable. A switch is provided on the handle for controlling the circuit and the parts are arranged in a manner such that the operator may use the same handle in different positions upon the tool and thereby control its operation and adapt it to various uses and positions of operation. In this device the pistol grip or handle was removably secured to the casing by screws, the electrical connection being established by means of an adapter block engaging protected contacts in connectors of both the handle and the casing. This arrangement necessitated the use of a screw driver or other implement to remove the holding means or screws and since one of the objects of the tool is to do away with spare parts, which may be lost or may be out of reach at the time when a change of position of the handle is desirable, it would therefore be of advantage to render the securing means for the handle accessible and operable by the operator independently of a screw driver or other implement.

The object of this invention therefore is to provide a two-position handle or grip hand tool with slideable or other readily disconnectable means between the tool and the handle and in addition thereto to provide a lock or latch which will insure the parts re-

maining in engagement after being applied in the desired position. 55

The foregoing is set forth in one embodiment in the following description and claims.

Referring to the drawings, Fig. 1 is a side elevation of the device; Fig. 2 is a rear end elevation; Fig. 3 is a rear end elevation of the main casing with the handle or grip removed; Fig. 4 is a bottom plan view with the handle or grip in position; Fig. 5 is a front elevation of the handle; Fig. 6 is a longitudinal sectional view of the adapter or plugging device; and Fig. 7 is a plan view of the same.

In the arrangement shown, 1 represents the main casing provided with a tool receiving chuck 2 constituting the tool operating member or device. 70

Within the main casing 1 is an electric motor for driving the chuck 2 and since the motor may be of any well known or preferred type it is not shown specifically and it forms no special part of the invention except in so far as it may enter the combination or organization. The main casing 1 is also provided with an end cap 3 secured 80

in any manner, not shown, to the main casing.

This cap is provided at its rear end with a connector frame 4 forming a rectangular opening in the end of the cap. 85

Projecting inwardly from the cap along the sides of the frame are inwardly extending flanges 5 provided with openings for receiving screws 6 clamping a connector or block 7 in place within the frame 4. This connector or block 7 is provided with a centrally 90

disposed longitudinally extending notch or recess 8 opening out through a recess 9 in the frame at the bottom, as clearly shown in

Fig. 3. In the bottom of the recess and flush with its bottom surface, is a pair of fixed 95

contacts 10, each of which is in the form of a screw extending through the block to the inside where its threaded end forms a binding post with the nuts 11 and 12. The frame is also provided along its lateral sides with 100

longitudinally outwardly extending rails or guides 13, each of which is grooved at 14 to receive a suitable engaging part carried by

the handle or grip as will appear. The frame 4 is further provided, preferably at 105

its upper end, with a stop or lug 15, shown

in Figs. 1 and 3, for limiting the movement of the handle as will be brought out. The frame 4 is still further provided, preferably at its lower end, with an outwardly extending latch lug 16 provided with an opening normal to the plane of the outer edge of the frame and adapted to receive a latch bolt 17 normally pressed outwardly by a spring 18, indicated in Fig. 1. This bolt or latch is held in place, operated and limited in its movement by a hand piece or pin 19 passing through a slot 20 in the side of the lug. As before indicated, the bolt is normally pressed outwardly so that its end projects beyond the outer edge of the frame 4 and it may be moved inwardly by the finger piece or pin 19 so that its outer end is flush with the outer edge of the frame 4. This lock or latch is utilized to hold the handle in place as will be brought out.

The casing 1, preferably on its lower side, is provided with a frame 21 similar in all respects to the frame 4 having its lateral guides opening out at the rear and provided with a stop at the front and latch or lock at the rear. This frame in like manner is also provided with a connector block similar to the block 7 and similar contacts. Both of these connector blocks are in the supply circuit to the motor so that if current be supplied to either of these blocks the motor will be driven.

The pistol handle or grip structure is preferably in the form of a closed loop, generally indicated at 22, and has a rear hollow gripping portion 23 extending in substantially a vertical direction and therefore provides a natural gripping device for the hand of the operator in manipulating the tool. This grip portion on the inside of the loop is provided with a switch 23' connected to one side 24 of the circuit. A second wire 25 leads, and is connected, to the two connectors of the handle or grip. The other incoming wire 26 is also connected to the connectors.

The handle or grip is provided with a horizontally disposed frame 27 similar to the frame 4 and provided with a recess corresponding to the recess 9, shown in Fig. 3, in the forward edge of the frame. This frame is provided with laterally projecting flanges 28 extending in opposite directions and adapted to nest and slide into the recesses 14 of the frame 21 upon the bottom of the casing. This frame 27 is also provided with inwardly projecting flanges corresponding to the flanges 5 for supporting a connector block similar in all respects to the connector block 7 and its central recess 8 is in alignment with the recess 9 of this frame. Its contacts correspond to the contacts 10 and are connected to the two wires 25 and 26, so that when the switch is closed, current is transmitted through these contacts. The

front of the grip or handle is also provided with a frame 29 similar in all respects to the frame 27 and provided with a notch corresponding to the notch 9, lateral flanges corresponding to the flanges 28 for engagement with the grooves 14 of the frame on the end gap, and with a connector block similar to the other connector blocks. In like manner this connector block has the binding post of its contacts connected in the circuits 25 and 26, so that these contacts will also be energized when the switch is closed.

In the drawings, the guides formed by the flanges 13 and recesses 14 on both the end cap and the bottom of the casing, as well as the flanges 28 on both the upper handle and front handle frames, are all tapered as shown so that the frames of the handle tend to seat snugly in the guides of the main drill portion and prevent lost motion, it is assumed, of course, that even tapered sliding engagement is limited by the stops 15 on the frames of the main casing and cap. When either of the frames of the handle are in engagement with the corresponding frame of the drill, the latch bolt 17 engages behind the frame and prevents its removal until the bolt is withdrawn.

It will be seen from the foregoing that the user on the job may, without the use of any additional tool or implement, remove the handle from one position and place it in another position, the handle seating in every instance and being prevented from accidental displacement by the latches provided for the purpose.

Since the contacts of the connector blocks are in the bottom of the grooves 8 no electrical contact is made between opposed connectors by the mere engagement of the handle so that an intermediate transfer device is provided and it is in the form of an adapter plug. This adapter plug comprises a substantially rectangular strip of insulating material 30 provided on each face with a pair of spaced recesses 31, each of which is below a free contact portion 32 of a leaf spring contact 33 secured in place by a suitable conductor rivet 34 passing through the strip and secured to the opposite leaf spring contact 33. Each of the free contact portions extends yieldingly beyond the corresponding face of the adapter so that when it is in place it is in a position to make contact with one of the contacts 10 of the connector blocks. In this way the circuit is closed from one connector block of the handle to the corresponding contact block of the main casing or cap.

Having described my invention, I claim:

1. In a motor hand tool, a motor in said casing, a handle or grip, hand operated interlocking means between said casing and handle, and suitable co-operating contacts carried by said casing and

handle and arranged for co-operating engagement upon the application of the handle.

2. In a motor hand tool, a motor casing, a motor in said casing, a handle or grip, hand operated interlocking means between said casing and handle, a contact block carried by said casing and provided with a recess, contacts carried by said block and at the bottom of said recess, and suitable contacts carried by the handle and arranged to co-operate with the contacts carried by the contact block when the handle is applied.

3. In a motor hand tool, a motor casing, a motor in said casing, a handle or grip having sliding interlocking engagement with said casing, an insulating contact block carried by said casing having a groove or depression extending in the direction of movement of the handle, contacts in the bottom 20 of said groove and suitable contacts carried

by said handle and adapted to co-operate with the contacts of said contact block when the handle is applied.

4. In a motor hand tool, a motor casing, a motor in said casing, a handle or grip, hand operated interlocking means between said casing and handle, a contact block carried by said casing and provided with a recess, contacts carried by said block and at the bottom of said recess, a contact block carried by said handle and provided with a groove extending in the direction of the sliding movement of the handle, contacts carried by said handle block and in the bottom of said groove and an adapter provided 30 with bridging contacts and arranged to nest in the grooves of the casing and the handle.

In testimony whereof I hereby affix my signature.

BLUFORD W. BROCKETT.
